Specification for Design.

Patented Nov. 12, 1912.

Application filed September 17, 1912. Serial No. 720,907. Term of patent 7 years.

To all whom it may concern:

Be it known that I, EARL B. THOMAS, a citizen of the United States, residing at Atlantic City, in the county of Atlantic and State of New Jersey, have invented a new, original, and ornamental Design for Medallions, of which the following is a specification, reference being had to the accompanying drawings, forming part thereof.

Figure 1 is a plan view of the obverse side of a medallion showing my new design.

Fig. 2 is a plan view of the reverse side of the medallion. Fig. 3 is an edge view.

I claim:

The ornamental design for a medallion as shown.

In testimony whereof I affix my signature in presence of two witnesses.

EARL B. THOMAS. [L.S.]
